United States Patent Office.

ERNST FRANK AND JOHN B. ADT, OF BALTIMORE, MARYLAND.

Letters Patent No. 106,147, dated August 9, 1870.

IMPROVEMENT IN APPARATUS FOR DRYING PHOSPHATES.

The Schedule referred to in these Letters Patent and making part of the same

To all whom it may concern:

Be it known that we, ERNST FRANK and JOHN B. ADT, of Baltimore, in the county of Baltimore and State of Maryland, have invented a new and improved Machine for Drying Phosphates; and we do hereby declare the following to be a full, clear, and exact description of the same, reference being had to the accompanying drawing making a part of this specification, in which—

Figure 1 is a longitudinal vertical section, and

Figure 2 is an end elevation.

This invention has for its object the drying of fish or such other animal substances as are used in the manufacture of ammoniated superphosphates, and the drying of such super and mineral phosphates as are used in the preparation of artificial guanos, or any other fertilizer, such drying being effected by giving the material a regular continuous movement over a furnace containing burning fuel.

In the drawing—

a is a sub-structure of masonry.

b is a metal hollow cylinder, fixed horizontally in suitable standards near each end, which rest on the foundation *a*.

c is a second cylinder, inclosed within the first, and projecting beyond the same at each end.

d is a toothed ring, fixed on the outside of the cylinder *c*, at its front end.

e are rollers, mounted in standards, which rest on the sub-structure *a*, said rollers being placed under the projecting parts of the cylinder *c*, near each extremity of the same, and serving to support the same, and aid in its rotation.

f are standards projecting upward from the sub-structure *a*, in advance of the front end of the cylinder *c*, from which standard arms *h* extend to one side, and bear a horizontal shaft, *i*, on which is placed the driving-pulley *k*, which receives motion, through belting, from the engine, and on which is also placed the cog-wheel *l*, which gears with the toothed ring *d*, and thus causes the cylinder *c* to rotate.

A is a cylinder, of less diameter than the cylinder *c*, and passing horizontally through the front end of the latter, opening into its interior, and supported in the standards *ff*.

m is a vertical receiver, which forms an elbow with the cylinder *A*.

n is a funnel, fixed in the top of the receiver *m*, through which the material to be dried is introduced.

o is a shaft, having radial arms, *r*, and placed crosswise of the upper part of the receiver *m*.

The function of the shaft and arms, which are made to revolve in any suitable manner, is to distribute the material evenly in the receiver and cylinder *A*.

B is a worm-shaft, placed lengthwise of the cylinder *A*, and extending out of the same, and bearing a pulley, *s*, on its projecting part, by which the motion is communicated to the worm-shaft that causes the latter to force the material to be dried into the cylinder *c*.

The latter is furnished with internal spiral ribs, *t*, by which, as the cylinder is revolved, the material therein contained is affected with a regular progressive motion lengthwise of the cylinder.

O are furnaces in the sub-structure *a*, from fires lighted in which the heat is furnished, which dries the material within the cylinder *c* as it travels over the furnaces, the lower part of the inclosing-cylinder *b* being removed for the purpose of exposing the cylinder *c* to the heat of the furnaces.

D is a compartment, into which the cylinder *c* discharges the dried material, from which compartment the material is removed through a hinged trap-door, *z*.

A packing, *v*, is placed around the cylinder *A*, in close contact with it and the head of the cylinder *c* for the purpose of preventing any loss of the material while passing from the receiver into the cylinder *c*.

Having thus described our invention,

What we claim as new, and desire to secure by Letters Patent, is—

The receiver *A*, screw-cylinder *c*, worm-shaft *B*, distributor *o* *r*, all combined and arranged as described.

ERNST FRANK.
JOHN B. ADT.
